SHOE LASTING MACHINE

**Walter I. Barnes, Rochester, N. Y., assignor of
one-half to Lee B. Carpenter, Rochester, N. Y.**

Application June 25, 1931, Serial No. 546,697

21 Claims. (Cl. 12—7)

My present invention relates to the manufacture of shoes and more particularly to the lasting thereof, so far as is concerned the operation of stretching and forming the upper upon the last, 5 and the invention has for one of its objects to provide an improved machine for manipulating the upper so that, in a rapid and efficient manner, the stretching tension upon the material of the upper will be equalized in all directions without 10 unnecessary strain in any one direction, so that the upper of the shoe will retain a shape that is exactly true to the conformation of the last.

To these and other ends, the invention resides in certain improvements and combinations of parts, all as will be hereinafter more fully described, the novel features being pointed out in the claims at the end of the specification.

In the drawings:

Fig. 1 is a side elevation of a lasting machine, broken away at top and bottom, constructed in accordance with and illustrating one embodiment of my invention, the same being capable of carrying out the improved method constituting part of my invention, the parts being in an initial position:

Fig. 2 is a similar view more in full and also partially broken away, showing the same parts in a different position in the cycle of operation, the operating elements omitted from Fig. 1 being shown in this view:

Fig. 3 is a front view of the head or upper portion of the machine, the lower portion being broken away:

Fig. 4 is a side view of the treadles or operating elements:

Fig. 5 is an enlarged detailed section through the upper gripping jaws in open position taken substantially on the line 5-5 of Fig. 1;

Fig. 6 is a similar view with the upper gripping jaws in closed position taken substantially on the line 6—6 of Fig. 2;

Fig. 7 is an enlarged horizontal section taken substantially on the line 7-7 of Fig. 3;

Fig. 8 is an enlarged vertical section taken substantially on the line 8-8 of Fig. 1;

Fig. 9 is an enlarged detailed vertical section through one of the lateral clamping devices; Fig. 10 is an enlarged section through one of the

upper gripping mechanisms taken substantially on the line 10-10 of Fig. 8;

Fig. 11 is an elevation of one of the upper gripping jaws in detail;

Fig. 12 is a fragmentary top plan view of the operating ends of the foot treadles,

55. Fig. 13 is an enlarged detail section taken verti-

cially through the carriage of the clamping means

Fig. 14 is a detail section on the line 14-14 of Fig. 13, and

Fig. 15 is a plan view of a last in position in the machine, showing an upper secured thereon in a manner adapting it to be manipulated in the machine illustrated and in accordance with my method of procedure.

Similar reference numerals throughout the several views indicate the same parts.

My improvements may be utilized to advantage in connection with or as an adjunct to a known method of lasting shoes (though this is not exclusively its application) and I will proceed to describe this method in a general way as an illustration in order to better explain my own improvements. Referring more particularly to Figs. 1, 8 and 13, A indicates a usual type of wooden last to which has been applied an upper B. The usual soft insole C of the shoe has been tacked to the last at D. The raw edges E of the upper have been loosely drawn above the insole. A soft pliable wire loop F has been stitched at G to the raw edge E about the toe terminating in loose ends H. A similar loop I has been stitched at K around the heel portion terminating in loose ends L. In accordance with the known method, the lasting is accomplished by successively twisting together, and thereby shortening and contracting the respective 85

shortening and contracting the respective loops, the loose ends H and the loose ends L. In the meantime, a suitable cement, known in the shoemaking art, is applied to the edges of the insole C beneath the raw edges E of the upper with the intent of ultimately fastening the latter thereto. The contracting loops, according to intention, draw the raw edges of the upper over the edges of the last in both instances and also draw them over the edges of the insole C to accomplish the cementing. This is done in a machine embodying certain elements devoted to this end, which I illustrate herein, and will later describe.

There is an objection to this general method which it is thought will be understood from the foregoing description. When the loop G, for instance, is tightened up by the aforesaid twisting operation, the greater force tending to draw the upper over the last is exerted at the point of the toe, because there is a direct longitudinal pull at this point that only later and progressively is converted into a lateral inward pull from the wire loop that draws over the lateral edges only because of a reaction against the toe. In other words, the toe portion of the edge of the upper, 110

as engaged by the wire loop, is subjected to an abnormal strain before the sides may be expected to close in at all. The result is that the material in the upper is subjected to too great a longitudinal strain before there is imposed upon it a sufficient lateral strain, so that the upper is apt to bridge the throat of the last longitudinally without being drawn down upon it at the sides. Perhaps this explanation, as a preliminary, will make clearer a description of the manner in which I remedy such defects, and I will now proceed to a description of the illustrated machine by means of which I do it. Reference will first be made to the last supporting and wire twisting mechanisms, which features, in a general way, constitute no part of my present invention.

Referring more particularly to Figs. 1 and 8, 1 indicates a jack pin supporting the last A in 20 the jack pin hole, which it loosely fits in the usual manner. The jack pin is mounted in a manner hereinafter described on a turntable 2 pivoted at 3 upon a base 4 held down by gibs 5 and 25 slideable upon a table or support 6 on a general frame 7 having legs 8. A spring latch 9 locks the turntable 2 with the base 4 by engaging notches 10 in the latter, selectively, to hold the last in positions with the toe pointing forwardly or rearwardly 180° apart. Suitably mounted at a rear 30 point on the table or support 6 on a stem 11 is a bearing head 12, upon which may be adjustably tilted by means of the bolts 13 a yoke 14. A spindle 15 has bearings 16 in this yoke, in 35 which it is both rotatable and longitudinally movable. The rotary movement is accomplished by a hand wheel 17, while longitudinal movement is effected against the tension of a spring 18 by means of a cable 19 running over a pulley 20 supported on an extension 21 of the yoke. This 40 cable 19 may run to a treadle (not shown) or other operating medium having a tendency to tighten it and draw upon the spindle. The point or head of the spindle 15 is suitably formed or fitted to take hold of the loose ends H and L 45 of the wire loops F and I and twist and draw them through its combined movements of rotation and longitudinal movement aforesaid. The contracting of the loops to stretch the upper in the old manner referred to is thus accomplished but with the shortcomings pointed out.

In the practice of my invention, I provide novel means for gripping the lateral edges of the upper and stretching it over the edges of the last before the contracting wires are put into operation at all. I further so grip the upper upon the ends of the last that it may not ride out of place under the strain resulting in an evenly lasted shoe that is not distorted from its proper position upon the last. Particularly is this latter true also with respect to pulling the lateral edges of the upper unevenly, which may result from the sole operation of contracting the wire loops, but is remedied by the equalizing drawing and stretching means that my invention contemplates and employs.

I will first continue a description of the last supporting and manipulating structure as mounted upon the turntable 2. Upstanding legs 22 on the turntable support the pivot 23 of a casting 24 where it is held rigid in different vertically tilted positions by a locking bolt 25 on the lugs taking into a slot in the said casting. The tilting adjustment is accomplished by means of hand screws 26 and 27 threaded in the casting and acting against the turntable 2 on opposite sides of the pivot 23. The jack pin 1 is pivoted on casting

24 at 28 to tilt forwardly and rearwardly slightly within the limits allowed by a stop shoulder 29 and the opposite wall of the cavity in which the jack is placed. In this latter wall is a spring pin 30 that tends to hold the pin with the shoulder 29 engaged. Slidable upon ways 31 on the casting 24 is a toe support 32 for the last that engages it on the underside in the manner shown in Fig. 1, the sliding adjustment permitting it to properly cooperate with lasts of different sizes. In consideration of the latter also, the base 4 carrying all the superstructure is slidable on the gibs 5 of the table.

When the last is placed upon the jack 1 and the toe support 32, it is held in part to resist upward pulling movement by cocking the jack pin in the socket thereof. This is accomplished in my device by means of a jaw 33 preferably faced with a not too soft rubber pad 34 that engages the heel of the last at the seam and which forces it forwardly onto the rest 32. Because of the contour of the heel, this jaw also itself resists upward movement of the last. It is mounted upon a lever 35 pivoted at 36 on the same lugs 37 on casting 24 that support the jack pin and is articulated by a hand screw 38 reacting against the casting. By this means the last is held while first one and then the other of the wire loops F and I are twisted by the spindle 15 after reversing the last end to end on the turntable, and it is also so held during the auxiliary lasting operation in conjunction with further means which I will now describe.

Referring more particularly to Fig. 8, the raw edges E of the upper, of course, project upwardly above the insole C when the last is in place on the machine, and I provide two pairs of jaws 39 adapted to grip the respective edges and which are vertically movable to pull them upwardly simultaneously, so that they act against each other and stretch the material of the upper closely transversely over the toe portion of the last. When the jaws are lowered to the gripping position shown in Fig. 8, they automatically open and as their hereinafter described supporting structure is raised, they are caused to first close together and then move bodily upwardly. Also, when they are lowered and opened, a presser foot 40 on the support engages the sole of the last or the insole C and limits their descent, establishing a proper relationship with the edges E. When the proper stretching tension has been imposed through the raising movement and before the jaws are lowered again to release the upper, it is clamped to the last at the sides, so that this transverse tension will not be relieved until the lasting is finished and while the longitudinal stretching is effected through the use of the wire loops in the manner first described. This clamping mechanism is best shown in Figs. 8 and 9 and, in the present instance, is constructed as follows:

Pivoted at 41 on brackets 42 projecting laterally on opposite sides of the last and support are two arms 43 carrying rotary and slidable threaded nuts 44. A hand screw 45 held against longitudinal movement is provided with right and left hand threads engaging these nuts respectively to spread the arms 43 or draw them together. Pivoted to the upper ends of the arms at 46 are levers 47 provided with clamping shoes 48 adapted to engage the edges of the upper and hold them tightly against the last. The point of contact of these shoes may be determined by set screws 49 threaded through the arm on opposite sides of the pivot 46 and reacting against lugs 50 on the arms 43. Or, the contact of the shoes may be

made self-adjusting to an extent through the medium of coiled compression springs 51 surrounding each set screw. Upon relieving or backing off the set screws, the arms 47 will be supported by one or more of the springs, so that their pressure will be resilient and yielding or partially yielding according to the adjustment of the set screw in the spring that is functioning, as will be understood from an inspection of Figs. 8 and 9. 5 When the function of resiliency is called into play, the clamping elements act as toggles, the centers 46 moving toward the line determined by the centers 41 and the points of contact of the shoes 48 tending, in a general way, to straighten out levers 10 43 and 47. This communicates an upward movement to the shoes 48 as they grip the upper, causing them to stretch the upper at the sides of the last as they go into engagement.

All of this clamping mechanism just described 20 is suitably mounted upon a carriage block 52 slideable upon the ways 31 independently of, but in the same manner as, the toe support 32 to a proper position of adjustment in accordance with the size of the last and also so that it may 25 be used on the heel portion, as well as upon the toe, if desired. Referring to Figs. 13 and 14 there is secured to this carriage block a squared vertical pin 105, upon which slides as a guide a bearing block 106. A cavity 107 in the top of this block 30 has slots 108 cut away in its side-walls to accommodate the rising and falling of the hand-screw 45 as, during adjustments the centers 44 swing on the centers 41. A disk or collar 109 secured to the middle of the hand-screw occupies 35 the cavity 107 and is the element which holds the hand-screw against end-wise movement.

It is the bearing block 106 upon which are formed the brackets 42 that support the pivots of the clamping arms 43, and the slidability of the 40 block is for the purpose of raising and lowering the arms so that the grippers 47 will engage at the desired point and at corresponding points on lasts of different sizes. The guide pin 105 is provided with rack teeth 110 with which engages 45 a spring pressed pivoted detent 111 on the block to hold the latter in positions of adjustment to which it has been elevated.

Coming now to the construction, mounting and operation of the gripping and stretching jaws 39, 50 a frame post 54 and two guide rods 55 rise vertically from and are rigidly secured to the general support 7 and are rigidly connected together at their upper ends by a crown piece 56. At an intermediate point, the guide rods 55 are connected by a fixed bridge piece 57 and fixed in the bridge member and the crown piece are two more guide rods 58 parallel to the guide rods 55 and to each other. Slidable upon the guide rods 58 is a primary head 59 which is raised bodily by a lever 60 pivoted at 61 to lugs on the bridge piece 57. The lever being of the first order, one end engages in a channel 62 in the head, while a cable 63 is connected to the other end and to a foot treadle 64 having a spring pawl 65 thereon cooperating with a ratchet 66 beneath the support. The head 59 is normally held lowered by gravity, being necessarily sufficiently heavy for this purpose. The presser foot 40 previously described is carried rigidly by this primary head and makes light contact with the last or insole when the head is lowered. In other words, as previously described, the grippers 39 and the presser foot always have a definite relationship, the latter acting as a stop for the former in the descent of the primary head. In

the illustration given, the lowermost reach of the presser foot and jaws, to strike a small or thin last, is given. Were the last thicker the head 59 would not be resting upon the bridge piece 57.

Fixed in bosses 67 in the primary head 59 is a pair of transverse horizontal guide rods 68, upon which slide blocks 69 that are adjusted toward and from each other by a hand screw 70 having right and left hand threads screwed into the respective blocks. A central bearing 71 for the hand screw holds it against endwise movement and as will be hereinafter explained, the two pairs of gripping jaws 39 are carried on these blocks and it is by this means that they are adjusted toward and from each other to be properly positioned to grasp the edges of the uppers on lasts of different widths.

Secondary heads 72 constitute mediums through which the jaws are so carried by the primary head. They each carry guide pins 73 pinned thereto, by which they slide vertically in the blocks 69, which sliding or raising and lowering movement is communicated to them by levers 74 pivoted at 75 to lugs on the crown piece 56 and engaging channels 76 in the respective heads 72 in the same manner as the lever 60 for raising the primary head 59. The opposite ends of the levers are connected by cables 77 with respective ends of a sprocket chain 78 on a sprocket 79 carried on a shaft having a bearing in a carriage 80 slideable on the guide rods 55. Another cable 81 connects this carriage with another treadle 82 associated with the treadle 64 and provided with an offset lug 83 which picks up and locks with treadle 64 after a partial movement of treadle 82, so that thereafter the two move farther together for purposes that will be explained.

On the opposite end of the sprocket shaft on carriage 80 is a miter gear 84 meshing with a 115 miter pinion 85 on the shaft 86 of a hand wheel 87 having bearings in lugs 88 on the carriage. It is obvious that, by turning the hand wheel and, through the gearing, the sprocket 79, the chain 78 through the cables 77 will equalize the initial or 120 normal positions of the secondary heads 72, so that the two pairs of gripping jaws 39 will properly position themselves with respect to opposite edges of the last to grasp the respective edges of the upper or one set of jaws may be adjusted 125 in advance of the other to exert a stronger pull on one edge of the upper than on the other according to conditions. Springs 89, shown broken away in Fig. 1 and connected respectively at their ends to the levers 74 and to the bridge piece 57, 130 normally hold the secondary heads 72 in the down position.

The gripping jaws 39 and the attendant mechanism for actuating them are respectively mounted in the secondary heads 72 in the following manner:

Referring first to Figs. 1, 5 and 6, a lug 90 on each secondary head 72 carries a sleeve 91 held thereto by upper and lower collars 92 and 93 fastened to the sleeve on opposite sides of the lug. Within the sleeve is a sliding plunger 94 having a pin 95 therein that projects a slot 96 in the surrounding sleeve and rests upon a lug 97 on the corresponding block 69 that rises and falls with the primary head 59. A plug 98 secured in association with the collar 92 stops the upper end of the sleeve 91 and between this plug and the upper end of plunger 94 is a coiled spring 99 that holds the plunger down when the sleeve rises, developing a relative movement between the two.

The gripping jaws 39 are of the form shown in detail in Fig. 11 and are pivoted in pairs at 100 to the lower projecting ends of the plunger 94, which is transversely slotted up to the point 5 shown in dotted line at 101 to accommodate them. The shafts 102 of these jaws cross in the manner shown in Figs. 5 and 6 and on each side of the crossing point is an actuating pin 103 fastened in the sleeve and extending through a slot 104 in the plunger 94. Therefore, when the sleeve 91 is raised, through the rising of a secondary head 72 and its boss 90, pin 103 thereon will close the gripping jaws 39, as in Fig. 6, and when it is lowered, the other pin 103 will open them, as in Fig. 5, which is the normal position, as is that of Figs. 1 and 8. Aside from the lateral adjustment, this is the only purpose of the secondary heads, which first move individually relatively to the primary head to operate the jaws and then with it 20 after the jaws have gripped the upper to produce the stretching action. This will be made clear by the following description of the general operation.

The treadle 64 is depressed and locked by the 25 pawl 65 on the ratchet, raising the primary head 59 and all of the parts carried by it, so that they will be out of the way while the last with the upper thereon is adjusted in its support. Treadle 64 is then released, lowering both primary and 30 secondary heads and carrying the normally open gripping jaws down to the positions of Figs. 1 and 8, ready to grip the edges of the upper. At the same time, the presser foot 40 on the primary head comes down into engagement with the last. The 35 treadle 82 is then depressed. This raises the secondary heads alone, lifting the jaw controlling sleeves 91 from the position of Fig. 5 to that of Fig. 6 to close the jaws on the upper but not move them vertically. Through lug 83, treadle 40 40 then picks up treadle 64 and depresses it, causing the primary head 59 to rise and carry with it, through blocks 69 fixed to it for vertical movement, the two primary heads drawing the gripping jaws upwardly and stretching the upper. The 45 lateral clamps 47 are now brought into use to hold the upper stretched while the treadle 82 is released and the secondary heads lowered to release the jaws, whereupon the further lasting with the wires, through the spindle 15, is proceeded 50 with as first described. Treadle 64 being locked depressed supports the gripping jaws clear of the last, though the slight relative drop of the secondary heads on the primary head has opened them.

55 It will be understood that a lasting machine constructed in accordance with my invention may be used otherwise than with the particular method of lasting with wire which I have described as being old in the art, though for the 60 reasons stated it adds greatly to the results obtained in such practices as in others. With the wire-lasting method, the edges of the upper are cemented to the edges of the insole C and with the previous stretching afforded by my invention the wire loops are enabled to flatten the said 65 edges down upon the cement in a more intimate manner because they are largely relieved from the greater strain of performing all of the stretching also and hence, draw flat against the 70 insole. With this wire-lasting, it is also customary to cement the outsole to the insole and upper, for which purpose the lasted bottom is ground to remove the stitching and release the wires, as well as, to subsequently roughen the 75 surface to make a better binding for the cement

and the outsole. In such cemented shoes, it has heretofore been difficult to draw the edges of the upper uniformly over the edges of the last and onto the insole so that there will be an equal area of cementing surface on the upper at each 80 side. This latter is just what my machine accomplishes with its equalized grip upon the two edges at the same time.

I claim as my invention:

1. In a shoe lasting machine, the combination with a last support, of pairs of gripping jaws adapted to engage the edges of an upper upon the last and draw it transversely over the same, means for pinching the upper against the last in a lateral direction, foot treadle means for 90 operating the gripping jaws and hand-operated means for operating the clamping jaws.

2. In a lasting machine, the combination with a last support, of means for engaging the edges of an upper upon the last and stretch it transversely over the same, means for pinching the upper against the last in a transverse direction, means for operating the upper engaging means and means for operating the pinching means, one of said operating means being hand operated 100 and the other embodying a foot treadle.

3. In a shoe lasting machine, the combination with a last support of a pair of clamping jaws mounted thereon, and means for actuating them relatively to clamp a last between them and hold 105 an upper in position thereon, each jaw embodying an arm pivoted to the support and carrying at its upper end a rocking contact member and set screws on opposite sides of the axis of the contact member acting between it and the arm 110 to limit the rocking movement.

4. In a shoe lasting machine, the combination with a last support of a pair of clamping jaws mounted thereon, and means for actuating them relatively to clamp a last between them and 115 hold an upper in position thereon, each jaw embodying an arm pivoted to the support and carrying at its upper end a rocking contact member and set screws on opposite sides of the axis of the contact member acting between it and the arm 120 and the arm to limit the rocking movement, together with springs associated with the set screws to act upon the contact member when the set screws are backed off.

5. In a shoe lasting machine, the combination 125 with a last support, of a vertically adjustable bearing block thereon, said bearing block having laterally extending brackets, a pair of clamping jaws comprising levers pivoted upon the brackets and carrying contact members and 130 means cooperating with the arms and having a bearing in the bearing block for actuating the contact members to clamp a last between them and hold an upper in position thereon.

6. In a shoe lasting machine, the combination 135 with a last support, a carriage movable thereon in a direction longitudinally of a last occupying the support and a bearing block adjustable vertically on the carriage, of a pair of clamping jaws mounted on the bearing block and means 140 also mounted on the latter for actuating the jaws relatively to clamp a last between them and to pinch an upper against the same.

7. In a shoe lasting machine, the combination with a last support, embodying a tiltable element, having a rocking jack pin thereon and a guide, and means for holding the tiltable element in different position of adjustment, of a toe support for a last on the jack pin slideable 145 on the guide, a carriage also slideable on the 150

- guide, a pair of clamping jaws mounted on the carriage, means for actuating them relatively to clamp a last between them and hold an upper in position thereon, a jaw in the tiltable element adapted to engage the heel of the last and cock the jack pin and means for operating the last-mentioned jaw. 80
8. In a lasting machine, the combination with a last support, and means for retaining a last and upper in fixed position thereon, of a superstructure embodying vertical guides, a head movable on the guides, gripping elements carried by the head and adapted to engage opposite edges of an upper on the last, a lever fulcrumed on the superstructure and engaging the head and a treadle connected to the lever. 85
9. In a lasting machine, the combination with a last support, and means for retaining a last and upper in fixed position thereon, of a superstructure embodying vertical guides, a head movable on the guides, and provided with laterally extending horizontal guides, laterally relatively adjustable carriage blocks movable on the last mentioned guides, and gripping elements carried by the carriage blocks and adapted to engage opposite edges of an upper on the last and means for operating the head to stretch the upper. 90
10. In a lasting machine, the combination with a last support, and means for retaining a last and upper in fixed position thereon, of a superstructure embodying vertical guides, a head movable on the guides, and provided with laterally extending horizontal guides, laterally relatively adjustable carriage blocks movable on the last mentioned guides, gripping elements carried by the carriage blocks and adapted to engage opposite edges of an upper on the last and means for operating the head to stretch the upper. 95
11. In a lasting machine, the combination with a last support, and means for retaining a last and upper in fixed position thereon, of a superstructure embodying vertical guides, a primary head movable on the guides and itself embodying guides, a gripping device adapted to engage the edges of the upper and embodying a pair of jaws, a secondary head movable on the guides of the primary head and directly carrying the gripping jaws, means for opening and closing the jaws through the relative movement of the heads, means for raising the secondary head to close the jaws upon the edges of the upper, and means for raising the primary head to stretch the upper. 100
12. In a lasting machine, the combination with a last support, and means for retaining a last and upper in fixed position thereon, of a superstructure embodying vertical guides, a head movable on the guides and itself embodying guides, a pair of grippers mounted on the head and embodying a fixed supporting element and a relatively movable actuating element for the jaws thereof, a head movable on the guides of the first mentioned head and carrying the actuating element, and means for operating the heads. 105
13. In a lasting machine, the combination with a last support, and means for retaining a last and upper in fixed position thereon, of a superstructure embodying vertical guides, a primary head movable on the guides and itself embodying guides, a pair of grippers mounted on the primary head and embodying a fixed supporting element and a relatively movable actuating element for the last. 110
14. In a lasting machine, the combination with a last support, and means for retaining a last and upper in fixed position thereon, of a superstructure embodying vertical guides, a primary head movable on the guides and itself embodying guides, a secondary head movable on the primary head guides, a pair of gripping jaws, a supporting plunger therefor carried by the primary head, a sleeve surrounding the plunger and carried by the secondary head, said sleeve being provided with means for actuating the jaws, and means for operating the heads. 115
15. In a lasting machine, the combination with a last support, and means for retaining a last and upper in fixed position thereon, of a superstructure embodying vertical guides, a primary head movable on the guides and itself embodying guides, a secondary head movable on the primary head guides, a pair of gripping jaws, a supporting plunger therefor carried by the primary head, a sleeve surrounding the plunger and carried by the secondary head, said sleeve being provided with means for actuating the jaws, a spring acting between the plunger and sleeve, and means for operating the heads. 120
16. In a lasting machine, the combination with a last support, and means for retaining a last and upper in fixed position thereon, of a superstructure embodying vertical guides, a primary head movable on the guides and itself embodying guides, a secondary head movable on the primary head guides, a pair of gripping jaws having crossed cam shanks, a supporting plunger for the gripping jaws carrying a pivot therefor, a sleeve surrounding the plunger and carried by the secondary head and further provided with pins engaging opposite sides of the cam shanks to open the jaws in one direction of movement and to close them in the other, and means for operating the heads. 125
17. In a lasting machine, the combination with a last support, and means for retaining a last and upper in fixed position thereon, of two vertically movable gripping elements arranged above the last support and adapted to engage the opposite edges of an upper thereon, a head associated with and supporting said gripping elements and upon which said gripping elements are relatively movable, and means for equalizing said gripping elements in their relative positions upon the head. 130
18. In a lasting machine, the combination with a last support, and means for retaining a last and upper in fixed position thereon, of a superstructure embodying vertical guides, two vertically movable gripping elements on said guides adapted to engage the opposite edges of an upper on the last, means on the superstructure connected to the gripping elements to raise one and lower the other proportionately with reference to the last, and means for raising both gripping elements simultaneously to stretch the upper over the last. 135
19. In a lasting machine, the combination with a last support and means for retaining a last and upper in fixed position thereon, of a superstructure embodying vertical guides, two vertically movable gripping elements on said guides adapted to engage the opposite edges of an upper on the last, a rotary element on the superstructure, 140

means associated therewith connected at its opposite ends to the respective gripping elements for joint movement thereof whereby one is raised when the other is lowered, and means for raising the gripping elements in unison to stretch the upper upon the last.

20. In a lasting machine, the combination with a last support, and means for retaining a last and upper in fixed position thereon, of a superstructure embodying vertical guides, a head movable on the guides, two gripping elements mounted on the head and adapted to engage opposite edges of an upper on the last, said gripping elements being relatively movable on the head, a device 10 slidable on the superstructure guides for effecting relative movement of the gripping elements with reference to the head, and means connected with said device for raising the head.

21. In a lasting machine, the combination with a last support, and means for retaining a last and upper in fixed position thereon, of a superstructure embodying vertical guides, a head movable on the guides, two gripping elements mounted on the head and adapted to engage opposite edges of an upper on the last, said gripping elements being relatively movable on the head, a carriage 15 slidable on the superstructure guides and embodying a hand wheel, a sprocket and a sprocket chain on the latter, connections between the ends of the sprocket chain and the respective gripping elements whereby one is lowered proportionately to the raising of the other, and means connected with the carriage for raising and lowering the head.
